DESIGN FOR A VENDING MACHINE

George E. Ball, Edgewood, R. I.

Application March 23, 1934, Serial No. 51,154

Term of patent 3½ years

To all whom it may concern:

Be it known that I, GEORGE E. BALL, a citizen of the United States, residing in Edgewood, county of Providence and State of Rhode Island, have invented a new, original, and ornamental Design for Vending Machines, of which the following is a specification, reference being had to the accompanying drawing, forming a part there-

The drawing is a perspective view of a vending machine embodying the design.

I claim:

The ornamental design for a vending machine as shown.

GEORGE E. BALL.
